UNITED STATES PATENT OFFICE.

WILLIAM G. HOWE, OF BOSTON, MASSACHUSETTS.

WINDOW-WASHING SEAT.

SPECIFICATION forming part of Letters Patent No. 310,057, dated December 30, 1884.

Application filed May 2, 1884. (No model.)

To all whom it may concern:

Be it known that I, WILLIAM G. HOWE, of Boston, in the county of Suffolk and State of Massachusetts, have invented certain Improvements in Window-Washing Seats, of which the following is a specification.

This invention has for its object to provide improved means for detachably securing a seat to a window-casing, so that it may serve as a support for a person, either in a sitting or standing position, while washing the outer surface of the window, or performing other operations, such as painting, glazing, &c.

The invention consists in a seat provided with adjustable arms arranged to grasp the wall of a building below the window-casing, and means for positively holding said arms in any positions to which they may be adjusted.

The invention also consists in certain details of construction, all of which I will now proceed to describe and claim.

Of the accompanying drawings, forming a part of this specification, Figure 1 represents a perspective view of a seat provided with my improvements. Fig. 2 represents a section on line *x x*, Fig. 3. Fig. 2^a represents a portion of the section shown in Fig. 2. Fig. 2^b is a side elevation of the locking device. Fig. 3 represents a top view. Fig. 4 represents a bottom view. Fig. 5 represents a section on line *y y*, Fig. 3.

The same letters of reference indicate the same parts in all the figures.

In the drawings, *a* represents a seat, which may be of rectangular or other suitable form. I prefer to make the seat of malleable iron cast in the desired form. Secured to or formed with the seat is a bar, *b*, located below the seat, and extending from front to back thereof, and provided on its upper surface with ratchet-teeth *b'*.

c represents a slide or block having a longitudinal aperture through which the bar *b* passes, the block *c* being adapted to slide on the bar. On the block *c* is formed a stout arm, *e*, which is adapted to bear against the outer side of the wall *w*, below the ledge *w'* of a window when the seat is in place, as shown in Fig. 2. The arm *e* may be adjusted to the thickness of the wall by sliding the block *c* on the bar *b*, suitable devices being provided for engaging the slide with the bar, and positively

holding the arm *e* in any position to which it may be adjusted. In the present instance I have provided holding devices composed of a block, *f*, having a longitudinal slot, which receives the portion of the sliding block *c* above the bar *b*, and teeth *f'*, adapted to engage the teeth *b'* of said bar, and a spring, *g*, adapted to press the block *f* downwardly and cause its teeth to engage with those of the bar *b*, and a cam-lever, *h*, pivoted in the upper portion of the block *f*, and adapted, when raised, as shown in Fig. 2^a, to bear on the upper part of the block *c* and raise the block *f*, thus disengaging its teeth from those of the bar *b*, leaving the block *c* and its arm free to be moved along said bar. When the lever *h* is restored to the position shown in Fig. 2, it allows the spring *g* to re-engage the teeth *f'* and *b'*, which hold the block *c* positively, so that the arm *e* cannot be moved away from the wall *w*. A slot, *i*, is provided in the seat to accommodate the blocks *c f* and lever *h*.

j j represent slides or bars adapted to slide in guides on the under side of the seat, and provided at their forward ends with downwardly-bent arms *j' j'*, adapted to bear against the inner side of the wall *w*, as shown in Figs. 1 and 2. The slides are adjustable to adapt the arms *j' j'* to the thickness of the wall, and are also provided with devices for positively holding them, so as to confine the arms against the wall. To this end the slides *j j* are in the present instance provided with teeth *l*, which are pressed by springs *l* against ratchet-teeth *m* on bars affixed to or formed on the bottom of the seat. The springs *l* bear against fixed guides *m'*. When it is desirable to adjust the slides *j*, they may be moved laterally, by means of downwardly-projecting handles *n*, until their teeth are disengaged from the teeth *m*, the slides being then free to move longitudinally. When the desired adjustment is effected, the springs *l* force the slides inwardly and cause the teeth *l m* to re-engage, thus locking the slides and preventing accidental movement of the arms *j* away from the inner side of the wall *w*. Set-screws *l'* may be employed to hold the slides *j* in engagement with the teeth *m*, said screws passing through the guides *m'*, as shown in Fig. 4. It will be observed that the wall is thus tightly grasped by the arms *e l*, so that the seat is firmly secured in

place and prevented from tipping in any direction. The side edges of the seat may be provided with set-screws p , working in tapped lugs p' on the seat. (See Fig. 1.) Said screws 5 are intended to bear on the window-ledge, in case the bottom of the seat cannot bear directly thereon, the adjustability of the screws enabling them to conform to the height of the ledge. The tapped lugs p' may be movable in 10 slots in the seat, so that they may be adjusted to the width of the window-sill, and may be positively held wherever adjusted by pins, set-screws, or other suitable means.

$r' r' r'$ represent vertical posts at the corners 15 of the seat-supporting side rails, s . Said posts are preferably tubular and threaded internally, so that longer vertical rods r' can be screwed into them to serve as guards for a person standing on the seat, their upper ends being connected, if desired, by a cord or chain, t . Said rods 20 may be lengths of gas-pipe, and when they are not required for use they may be readily removed from the socketed posts r . Instead of being screwed into the sockets r , the rods r' 25 may be held in said sockets by friction.

u represents an arm or bracket adapted to be secured either to one of the posts r or to one of the rods r' , and hold a pail or other vessel that may be required. Said bracket has two 30 bosses, $v v'$ —one adapted to enter the socket of one of the posts r , and the other, of smaller size, adapted to enter the end of one of the tubular rods r' .

All the parts of my improved seat are 35 preferably made of metal. The upper surface of the seat may be provided with a covering of fiber, such as is used for chair-seating. The parts of the arms j' which bear against the wood-work may be covered with rubber or 40 other comparatively yielding material to prevent injury to the wood. The arm e may be similarly covered, if desired, although in most

cases it will not be necessary. It is obvious that more than one arm e may be employed. I do not confine myself to making all of the 45 arms adjustable. Either the arm e or the arms $j' j'$ may be permanently attached to the seat, so as to be non-adjustable.

The adjusting devices for the arms and the means for positively holding the arms after adjusting them may be variously modified. 50

I claim—

1. A window-washing seat having toothed bars m , arms $j j'$, having hooks at their inner ends, and ratchet-teeth engaging the teeth on bars m , block c , through which a ratchet-bar 55 on the seat passes, and locking mechanism, whereby the ratchet-bar and block c may be held in engagement, all combined and relatively arranged, substantially as stated. 60

2. In combination, a slotted seat provided with a longitudinal rack-bar and a movable block on a movable supporting-bracket engaging said rack, said seat also having side rack-bars 65 engaging adjustable supporting hook-arms, the specified elements relatively arranged substantially as shown and described.

3. The combination, with the seat a , of the hooked bars $j j'$, adjustably secured thereto, the block c , having bar c , also adjustably secured to the seat, and the adjustable bearing-screws p , arranged, as described, to bear on the window-ledge, all substantially as shown 70 and described.

4. The bracket u , provided with bosses $v v'$ 75 of different sizes, as set forth.

In testimony whereof I have signed my name to this specification, in the presence of two subscribing witnesses, this 29th day of April, 1884.

WILLIAM G. HOWE.
